CLAIM

The ornamental design for a set of wireless controller sleeves, as shown and described.

DESCRIPTION

FIG. 1 is a perspective view of a set of wireless controller sleeves showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof;

FIG. 9 is an enlarged view of portion 9 shown in FIG. 2;

FIG. 10 is a front perspective view of its use state;

FIG. 11 is a front perspective view of its extended status; and,

FIG. 12 is an exploded perspective view of its extended status.

The dash-dash broken lines in the drawings depict portions of the set of wireless controller sleeves that form no part of the claimed design.

The dot-dash broken lines represent boundaries of the enlarged portions and form no part of the claimed design.
